UNITED STATES PATENT OFFICE.

LUTE BROWN, OF FAIRMONT, WEST VIRGINIA.

ELASTIC CONNECTION.

1,165,839.

Specification of Letters Patent. Patented Dec. 28, 1915.

Application filed July 21, 1911. Serial No. 639,720.

To all whom it may concern:

Be it known that I, LUTE BROWN, a citizen of the United States, residing at Fairmont, in the county of Marion and State of 5 West Virginia, have invented certain new and useful Improvements in Elastic Connections, of which the following is a specification.

My invention relates to improvements in 10 garment supporters and has for its leading object the provision of an improved limb encircling resilient band for use in supporting hose or holding sleeves in desired raised position.

15 The further object of my invention is the provision of a device of this character which will dispense with the employment of elastic in said band and which will provide an improved device whose efficiency 20 will not be impaired on account of excessive perspiration which soon rots the ordinary elastic band in general use.

Other objects and advantages of my improved garment supporter will be readily 25 apparent by reference to the following description taken in connection with the accompanying drawings and it will be understood that I may make any modifications in the specific structure shown and described 30 within the scope of my claim without departing from or exceeding the spirit of the invention.

Figure 1 represents a view of an arm band constructed in accordance with the 35 principles of my invention. Fig. 2 represents a sectional view thereof. Fig. 3 represents a sectional view on the line 3—3 of Fig. 1, and Fig. 4 represents a plan of the cut blank ready to be formed into the 40 sheath for the resilient member of my device.

In the drawings, the numeral 1 designates the main band of my device, while secured upon said band near one end thereof is the 45 metal casing 2. Said casing, as is most clearly shown in Fig. 3 is of flat shape and has struck from the portions on the under side thereof the tongues 3 adapted to be

forced through and clamped against the strip 1 to firmly secure the casing thereon. 50

Struck from the upper portion at one end of the casing is an inwardly extending tongue 4, while struck from the under portion of the casing and extending upward into the casing are the tongues 5, one end of 55 the flat extension spring 6 being secured between the said tongues which serve to firmly hold the same in place and prevent withdrawal of the spring from the casing. Secured to the opposite or loose end of the 60 said spring 6 and having its end contained within but slideable with respect to the casing 3 is the tab or short strip 7 bearing the socket 8 for engaging the fastening button 9 carried by the opposite end of the strip 1 65 from that to which the casing is secured.

From the foregoing description taken in connection with the accompanying drawings the construction of my improved garment supporter will be readily understood 70 and it will be seen that the spring 6 will yield to allow of the increase of the size of the space inclosed by the band 1 and tab 7 while tending to draw the tab back within the casing upon relaxation of the expanding tension and that the said spring will 75 consequently impart the desired and essential resiliency to the device, while the casing protects the spring from moisture or perspiration which might impair the efficiency 80 of the spring, the band or strip being of material which will not be affected deleteriously by said moisture. It will further be observed that the strip 1 extends beneath the casing 3 and prevents the same from 85 coming into contact with the garment or limb of the wearer and prevents rust stain by the casing when the same is damp.

I claim:

In an elastic connection, the combination 90 with a rectangular casing open at both ends and formed from a single piece of sheet metal, of a sheet metal tab having a tongue on one end thereof, slidably mounted in said casing, the said casing having a lug 95 struck from the central portion of one wall

at one end thereof and extending inwardly, a pair of lugs struck from the opposite wall of the casing, extending inwardly, and arranged on opposite sides of the first mentioned lug, and a flat tension spring secured to the tongue on the said tab at one end and extending between the lugs at the other end so that the pair of lugs on one wall will bear against one side of one end of the

spring and the lug on the other wall will ¹⁰ bear against the opposite side of said end of the spring to maintain it in position.

In testimony whereof I affix my signature, in the presence of two witnesses.

LUTE BROWN.
